ADJUSTING MEANS FOR CHAIN WRENCH

Leroy K. Selfridge, Portland, Oreg.

Application May 19, 1947, Serial No. 748,917

2 Claims. (Cl. 81—66)

1

This invention relates to an improved wrench having a flexible gripping element adapted to bind and grip round objects such as pipes and also angular objects such as nuts and bolt heads.

Objects of the present invention are to provide a wrench having a flexible gripping element which is particularly adaptable to use in confined places and to objects such as pipes or bolt heads lying closely adjacent a wall surface or other obstruction which would prevent the effective manipulation of a conventional wrench, to provide a wrench having a chain grip to engage objects of any shape, to provide a wrench with an encircling gripping element having a ratchet type action to tighten or loosen objects where there is limited freedom for handle movement, and to provide an exceptionally sturdy though economical construction capable of exerting an unusually powerful grip on smooth cylindrical objects which are difficult to grip with conventional wrenches.

The gripping element of the present wrench comprises a flexible member, preferably in the form of a link chain for heavy work, which, by a novel arrangement and pivotal mounting of the parts, is adapted to exert an extremely powerful gripping action upon an object to be turned or twisted. The gripping action of the flexible member is such that the grip may be tightened in any angular position of the wrench and the object may be turned effectively with a very small amount of handle movement. The construction permits a slight amount of reverse movement of the handle to loosen the chain grip to readily slip back and obtain a new hold on the object with a relatively small amount of lost motion in the loosening and tightening movements. This desirable mode of operation is accomplished by removably securing one portion or end of the chain grip in an anchor member pivotally mounted on a handle. A bight is formed in the chain on one side of the anchor member to encircle and grip the object to be turned, and another portion or end of the chain is adjustably anchored in the handle. Between the handle and the work engaging bight the chain is trained around a fulcrum guide surface at a distance from the pivotal mounting of the handle so that relative movement of the handle in one direction with respect to the anchor member shortens and tightens the chain in the bight. When the chain has been pulled tight in this manner the force applied to the handle thereby continues to hold the chain tight on the object with a powerful force related to the turning effort which must be exerted to turn the object. When the handle is moved in the oppo-

2

site direction the chain is loosened sufficiently to slip on the object with a ratchet-like action.

These and other objects and advantages will become apparent from the following description in connection with the accompanying drawings illustrating a preferred embodiment of the invention.

In the drawings:

Figure 1 is a view of the wrench applied to a pipe;

Figure 2 is a cross sectional view taken on the line 2—2 of Figure 1;

Figure 3 is a fragmentary perspective view of the handle; and

Figure 4 is a sectional view taken on the line 4—4 of Figure 1 showing the locking means for adjustably anchoring one end of the flexible gripping element.

The various operative parts of the wrench are carried by or mounted on a hollow handle 10. A chain anchor comprising a slider 11 is mounted to slide longitudinally within the hollow handle and is adapted to lock in different positions to adjust the useful length of the chain which is allowed to extend from the handle. One side of the handle is provided with a longitudinal slot 12 through which a thumb or finger piece 13 projects, the opposite sides of the slot having recesses 14 to engage detents 15 on the slider to hold it in different selected positions. A spring 16, carried by the slider, normally urges the detents into these recesses, but by pressing the thumb or finger piece 13 into the handle the detents may be disengaged from the recesses to move the slider to any desired position.

A pin 17 secures one end of the gripping chain 18 to the slider, allowing the other end of the chain to extend out of the end of the handle. The handle has a bracket arm 19 alongside the chain and provided with a pivot pin 20 for pivotally mounting a gripping anchor member 21. The member 21 has an opening 22 through which the chain passes and a notch or hook 23 for removably engaging and anchoring a pin 24 on the free end 45 of the chain.

Thus, when the pin 24 is engaged in the notch 23, a portion of the chain near the free end may be looped into a bight 25 to encircle and grip an object to be turned. Because of the articulating 50 pin connected joints between the chain links, the chain is adapted to accommodate itself approximately to the surface contour of any angular or curved surface. The chain links are provided with hardened teeth 26 to bite into smooth surfaced objects such as pipes to prevent slippage

of the chain. When a pipe 30 or other object is gripped by the chain it is pulled into engagement with other teeth 31 formed on the gripping member 21 to assist the teeth 26 in preventing slippage. Preferably, all these teeth are inclined in the manner shown to bite in one direction of twist and slip in the reverse direction to facilitate a ratchet-like action, as will presently be described. The numeral 32 designates a wall portion or bridging member interconnecting opposite side walls of the member 21 on the opposite sides of the opening 22 to provide stiffness and rigidity in this member and to serve as a chain guide defining another wall of the opening 22.

When the handle 10 is swung about the pivot 20 in the direction of the arrow 35, it is apparent that the chain in the bight 25 will be slackened so that the chain and wrench as a whole will be free to slide around the pipe in a counterclockwise direction. The previously mentioned inclination of the teeth 26 and 31 permits sliding in this direction. By reason of the fact that the chain is trained over an arcuate guide surface 36 forming a wall of the opening 22 at a distance from the pivot pin 20, any movement of the handle in a clockwise direction, as indicated by the arrow 37, causes a certain length of chain to be pulled through the opening 22 to contract or tighten the bight 25. The arcuate surface 36 thereby acts as a fulcrum or drum upon which a powerful leverage is exerted by the handle to wind up a portion of the chain as the handle rotates with respect to the member 21. After the chain is pulled tight on the pipe 30, so that the handle can no longer rotate with respect to the member 21 to pull through more chain, the wrench must rotate as a whole to twist the pipe. In this way the turning effort exerted on the pipe by force applied to the wrench handle also exerts a contractive gripping force upon the chain in proportion to the turning force exerted upon the pipe. With this direction of twist the teeth 26 and 31 bite into the pipe and do not permit slippage. Since the handle 10 has a wide range of angular movement on the member 21, there is no practical limit imposed upon the contraction of the chain bight if strong resistance is encountered in attempting to turn the object. In most conventional pipe wrenches the amount of clamping or biting action is positively limited by design, so that no amount of force on the wrench handle is effective to increase the clamping action beyond a certain point. On a pipe that is hard to turn, most conventional wrenches, therefore, tend to take a shallow bite and then slip on the pipe, scraping off a skin of metal and automatically losing their grip. It is impossible for the present wrench to lose its grip in this manner.

It will also be apparent that the present wrench may be used on pipes very close to a wall surface, or even lying against such a surface if any part of the pipe can be pulled out sufficiently to pass the free end of the gripping chain between the pipe and the wall. The slider 11 may then be pulled up and anchored at a point to place the handle in the most advantageous position for doing the work required. Only a very small handle movement is required to operate the wrench because the inherent ratchet-like action enables the gripping chain to be tightened on the object in any position of the handle so that the full available handle stroke may be used to turn the object.

The gripping element need not necessarily be a

link chain of the particular type shown. For certain purposes a metal or leather band or strap may be substituted for the chain. A leather strap would be advantageous, for instance, for use on more fragile objects such as screw caps on bottles and jars, and for objects having polished surfaces such as nickel or chromium plated pipes where the usual biting teeth would be objectionable. Such a strap is capable of exerting a powerful torque without flattening or crushing the object to which it is applied.

Various other changes may be made in the construction, arrangement and proportion of parts, and all such modifications within the scope of the appended claims are included in the invention.

Having now described my invention in what manner the same may be used, what I claim as new and desire to protect by Letters Patent is:

20 1. A pipe wrench comprising a hollow tubular handle having a longitudinal slot on one side of the handle, a sliding anchor in said handle, a thumb piece on one side of said anchor projecting out through said slot to move said anchor, detents on said one side of said anchor, a spring on the opposite side of said anchor having sliding engagement with the interior of said handle, a series of detent engaging means in said handle spaced along said slot to secure said anchor in different adjusted positions, a gripping chain having one end attached to said sliding anchor within said handle, a pivot on one end of said handle at said one side of the handle, a pivotal anchor member having one end mounted on said pivot and having a free end extending across said end of the handle, means on said free end of said pivotal anchor member for detachably securing the other end of said gripping chain, and a curved guide surface for the chain forming one wall of an opening in said end of the handle and extending partially around said pivot at a distance from the pivot axis to form a fulcrum for tightening said gripping chain around an object upon relative pivotal movement of said handle and pivotal anchor member, the opposite side of said handle having a smooth, uninterrupted exterior surface extending the full length of the handle for grasping the handle to apply said relative pivotal movement.

50 2. A pipe wrench comprising a hollow tubular handle having open ends and a longitudinal slot on one side of the handle extending from one end of the handle and terminating at a point near the other end of the handle, a sliding anchor in the handle having a thumb piece projecting out through said slot to move said anchor, detents on said sliding anchor adjacent said thumb piece, detent engaging means in said handle spaced along said slot, a spring member on said sliding anchor having sliding engagement with the interior of said handle to urge said detents toward said detent engaging means to lock said anchor in selected positions, a pipe gripping chain having one free end and one end attached to said sliding anchor within the handle, said chain and sliding anchor being insertable into said one end of the handle, a pivot on the other end of the handle at said one side of the handle, a pivotal anchor member having one end mounted on said pivot and having a free end extending across said other end of the handle, notches in said free end of said pivotal anchor member for detachable engagement with said free end of said gripping chain, and a ful-

70

crum for tensioning said chain having a guide surface for the chain extending around one side of said pivot and into said other end of the handle toward the terminus of said slot, the opposite side of the handle having a smooth, uninterrupted grasping surface extending the full length of the handle.
